X-RAY GENERATOR

Zed J. Atlee, Elmhurst, and Howard W. Brackney, Chicago, Ill., assignors to General Electric X-Ray Corporation, Chicago, Ill., a corporation of New York

Application October 2, 1941, Serial No. 413,264

6 Claims. (Cl. 250—147)

This invention relates in general to roentgenology and has more particular reference to an X-ray generator having an improved window structure for the emission of X-rays therethrough, the invention relating more especially to an X-ray generator particularly well adapted for use in crystallography and, to that end, having a plurality of X-ray transmitting windows displaced angularly on the envelope with respect to the source of X-rays in the generator.

An important object of the present invention resides in providing, in an X-ray generator having an envelope and an anode forming a source of X-rays within the envelope, an improved window construction in the envelope to provide for the egress of X-rays substantially without hindrance; a further object being to utilize a beryllium disk as a window means for the substantially unhampered transmission of X-rays therethrough; a still further object being to provide simple means for the mounting of the beryllium disk on the envelope, which is usually of glass.

Another important object is to provide an improved X-ray generator particularly adapted for use in crystallography, the generator comprising an envelope containing an anode forming a source of X-rays and the envelope being provided with a plurality of windows angularly displaced on the envelope with respect to the X-ray source, whereby rays transmitted through any of the windows may be utilized.

Another important object is to provide an improved X-ray window structure for X-ray generators by drawing a neck forming a window opening in the envelope of the generator and by fixing a plate of material substantially transparent to X-rays on said neck opposite the opening defined thereby; a further object being to utilize beryllium as a window-pane material substantially transparent to X-rays; a still further object being to provide for securing the beryllium window element on the glass envelope material at said neck; yet a further object being to utilize a window mount comprising a ring-like element of nickel steel, or other suitable material, for mounting the beryllium window element on the glass envelope.

These and numerous other important objects, advantages, and inherent functions of the invention will be fully understood from the following description, which, taken in connection with the accompanying drawing, discloses a preferred embodiment of the invention.

Referring to the drawing: Figure 1 is a side view, partially sectionalized, 55

of an X-ray tube embodying the present invention; and

Figures 2 and 3 are sectional views taken substantially along the lines 2—2 in Figure 1 and 5 3—3 in Figure 2.

To illustrate the invention, we have shown on the drawings an X-ray generator 11 comprising an anode structure 12 embodying a target 13, a cathode structure 14 embodying an electron source comprising a filament 15, and an envelope 16 enclosing the anode and cathode structures.

The generator illustrated is particularly well adapted for crystallography, that is to say, the examination of materials by observation of diffraction characteristics when exposed to X-rays. Such analysis of materials may be accomplished by exposing the same to X-rays and recording the X-ray diffraction characteristics of the material being examined, as by photographing the same on sensitized film.

The radiation from an X-ray generator consists of a continuous, or "white," spectrum, the wave length and intensity distribution of which depends largely upon the electrical potentials at which the generator is operated, it being understood, of course, that X-rays are generated at the target 13 by impingement thereon of electrons emitted by the filament 15. Electrons, in turn, are emitted by the filament when the same is electrically energized, as by the flow of electrical current therethrough under the influence of electrical potential applied to the filament. Electrons emitted by the filament are caused to impinge upon the target 13 under the influence of electrical potential applied between the anode and the cathode filament.

The target 13 may comprise any preferred target material, such as tungsten, molybdenum, copper, nickel, cobalt, iron, chromium or other desired target material, the choice of a suitable target material for X-ray diffraction analysis depending upon the type of specimen to be examined, the particular technique employed, and the sort of information sought. The X-ray spectrum of the rays produced by a generator depends upon the type of target material employed in producing the rays. Each target material has its own individual spectral characteristics, each spectrum comprising a relatively few lines, each having a specific wave length, depending only upon the type of target material employed. The spectra of the various target materials are entirely independent of the operating potential of the generator above a minimum voltage, which minimum voltage also is characteristic of the target mate-

rial. Any suitable target material may, of course, be employed for X-ray diffraction analysis, provided, of course, the material of the target and hence its "line" spectrum is known, otherwise, the spectral lines caused by the target material in the spectrograph of the material being examined may be mistaken for lines supposedly caused by the test sample, and it will be obvious from the foregoing that the particular materials to be examined by diffraction may best be examined by using particular targets.

The target 13 may comprise a rectangular button set in the end of the target support afforded by the anode structure 12, and the anode structure 12 may be mounted in any suitable or preferred fashion in the envelope. Since the envelope preferably comprises a glass tube, the anode structure will ordinarily be mounted on a suitable envelope seal at one end of the envelope and thereby supported in place, and the cathode 14 preferably comprises a suitable head which may be supported and sealed upon a suitable envelope seal at the other end of the envelope. Conductors for energizing the electron producing filament 15 may extend outwardly of the envelope through the cathode seal, and the cathode end of the tube may be fitted with a ferrule 17 carrying a base 19 for connecting the filament conductors with a suitable external source of power for energizing the filament for electron emission.

It will be noted that the filament is of elongated character and is supported in a groove 21 formed in the cathode head, whereby electrons emitted by the filament, when energized, will be focused substantially along a line on the target parallel to the longitudinal axis of the filament. To aid in focusing the electron stream, the cathode structure may include a skirt-like shield 22 projecting therefrom in position encircling the facing end of the anode, the target carrying end of the anode being immersed in said shield.

Any suitable source of external power may be used to cause electrons emitted by the filament 15 to impinge upon the target by connecting such external source of potential between one of the filament conductors and the anode stem 23 which is electrically connected through the anode structure with the target 13 which extends outwardly of the envelope through the anode seal. The stem 23 may also contain conduits 25 to provide for the circulation of a cooling fluid into and out of the anode structure from a suitable external source of cooling fluid, the interior of the cathode structure being preferably hollow to allow the cooling medium to circulate therethrough and thereby carry off the heat generated at the anode as a result of electron impingement upon the target.

X-rays generated at the target as a result of electron impingement thereon may travel in all directions outwardly of the target in a zone extending substantially at right angles with respect to the longitudinal axis of the generator. In the interests of safety, it is desirable to permit only such rays as are required to escape outwardly of the envelope and, to this end, the envelope 11 preferably, though not essentially, comprises glass which is substantially impervious to X-rays in order to prevent egress of unusable and unwanted X-rays. The envelope may comprise a hard glass of the borosilicate type, such as Corning No. 705 A. J., which is substantially opaque to X-rays of the wave length of the K-alpha line

of copper radiation, that is to say, the rays produced by activation of a copper anode.

The skirt-like screen 22 also may have some X-ray screening effect. In order to insure the retention of unwanted X-rays, we may provide an annular sleeve 27 upon the outer surfaces of the envelope opposite the target-carrying end of the anode, said sleeve preferably comprising the split parts 29 suitably clamped together around the envelope by means of suitable fastening screws 31. This sleeve may comprise material opaque to X-rays for the purpose of confining within the envelope all except desired useful X-rays.

It is desirable, however, to allow all useful X-rays to have substantially unhampered exit from the X-ray source outwardly of the envelope. To this end, the envelope is formed with drawn necks 33 forming openings therein angularly displaced around the envelope with respect to the target 13, there being, in the illustrated embodiment, four necks 33 relatively displaced by 90° with respect to the target 13. The skirt-like shield 22 also is formed with perforations 35 in alignment with the envelope openings defined by the necks 33.

The space within the envelope, of course, is necessarily maintained at low pressure, and in order to seal the envelope at the openings defined by the necks 33, we provide window-panes 37 sealed on the necks 33 in position closing the openings defined thereby. The panes 37 are disks or plates of material, such as beryllium, which is substantially transparent to X-rays so that useful rays may pass, freely and substantially without obstruction, from the source at the target 13 outward through the panes 37. Beryllium, however, is difficultly sealable to glass, and in order to attach the pane elements 37 on the necks 33, we provide pane mounting elements 39 preferably comprising short sleeves or rings of suitable material, such as Fernico. One end of each mounting element 39 is sealed on the corresponding neck 33, as by means of a glass-to-metal seal 41, and the window element 37 is sealed at its edges in an annular seat 43 formed in the mounting element 39, the beryllium disk 37 being sealed on the mounting element 39 as by silver solder brazing.

The foregoing window structure provides not only a vacuum tight seal at the envelope openings defined by the necks 33, but also affords substantially unimpeded X-ray exit through the beryllium window-pane elements 37. The window structures comprising the necks 33, the mounting elements 39, and the substantially X-ray transparent pane 37, extend in corresponding openings 45 formed in the annular sleeve element 27, so that useful X-rays developed in the generator may, by operating the same, be made available at the outer ends of the openings 45.

While the window construction of our present invention is particularly well suited for use in a multiple window generator of the sort herein illustrated for crystallography, it will be obvious that the invention is not necessarily limited to a multiple window construction but may be used to advantage wherever X-ray transparent windows are required.

It is thought that the invention and its numerous attendant advantages will be fully understood from the foregoing description, and it is obvious that numerous changes may be made in the form, construction and arrangement of the several parts without departing from the spirit

or scope of the invention, or sacrificing any of its attendant advantages, the form herein disclosed being a preferred embodiment for the purpose of illustrating the invention.

The invention is hereby claimed as follows:

1. An X-ray generator comprising a sealed envelope, anode and cathode means within said envelope, said envelope comprising a tubular glass portion surrounding said anode and having an opening therein opposite the anode, a metal mounting ring comprising an alloy including nickel as an alloy constituent thereof and having a coefficient of expansion such as to permit said alloy to be sealed with glass and soldered to beryllium, said ring being sealed on said envelope at said opening, and a pane of beryllium sealed on said ring in position closing said opening.

2. An X-ray generator comprising a sealed envelope, anode and cathode means within said envelope, said envelope comprising a tubular glass portion surrounding said anode and having an opening therein opposite the anode, a metal mounting ring comprising an alloy containing nickel and iron sealed on the envelope at said opening, and a pane of beryllium sealed on said ring in position closing said opening.

3. An X-ray generator comprising a sealed envelope, anode and cathode means within said envelope, said envelope comprising a tubular glass portion surrounding said anode and having an opening therein opposite the anode, a metal mounting ring sealed on the envelope at said opening, said ring comprising a metal alloy including nickel as an alloy constituent thereof and having a coefficient of expansion such as to permit said alloy to be sealed with glass and soldered to beryllium, a pane of beryllium, and silver solder sealing said pane on said ring in position closing said opening.

4. An X-ray generator comprising a sealed en-

velope, anode and cathode means in said envelope, said envelope comprising a tubular glass portion surrounding said anode and having a plurality of openings formed therein and disposed opposite and radially with respect to the anode, a mounting ring comprising an alloy including nickel as an alloy constituent thereof and having a coefficient of expansion such as to permit said alloy to be sealed with glass and soldered to beryllium, said ring being sealed to the envelope at each of said openings, and a plate of beryllium sealed in each of said rings.

5. An X-ray generator comprising a sealed envelope, anode and cathode means within said envelope, said envelope comprising a tubular glass portion surrounding said anode and having a plurality of openings formed therein and disposed opposite and radially with respect to the anode, a mounting ring comprising an alloy of nickel and iron sealed to said envelope at each of said openings, and a plate of beryllium sealed in each of said rings.

6. An X-ray generator comprising a sealed envelope, anode and cathode means within said envelope, said envelope comprising a tubular glass portion surrounding said anode and having a plurality of angularly displaced openings therein opposite and radially of said anode through which openings useful X-ray beams may be projected from the anode in a plurality of directions radially of the anode, a metal mounting ring, said ring comprising a metal alloy including nickel as an alloy constituent thereof and having a coefficient of expansion such as to permit said alloy to be sealed with glass and soldered to beryllium, said ring being sealed to the envelope at each of said openings, and a pane of beryllium soldered to each of said rings.
